UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

CEMENTING APPARATUS.

1,377,319.

Specification of Letters Patent. Patented May 10, 1921.

Application filed December 17, 1918. Serial No. 267,190.

To all whom it may concern:

Be it known that I, JOHN W. COSGROVE, a citizen of the United States, residing at Medford, in the county of Middlesex and 5 State of Massachusetts, have invented certain Improvements in Cementing Apparatus, of which the following description, in connection with the accompanying drawings, is a specification, like reference characters on the drawings indicating like parts in the several figures.

My invention relates to apparatus for the application of cement, being especially useful in connection with the cementing of the 15 uppers of tennis shoes for the attachment of the foxing.

In work of the character indicated above, the cement which secures the foxing to the upper must be applied in a band, the edge of 20 which toward the top of the shoe should be uniform and symmetrical with relation to the shoe bottom, so that it shall not project at any point beyond the foxing strip and thus deface the upper. An object of my invention is to shield the work effectively, as 25 the upper at the foxing line, against the overrunning of cement. This I accomplish by the employment of a movable cement-applying member and a member situated 30 beside it and arranged to define the line between the coated and uncoated areas, the last-named member extending through substantially the full length of the path of movement of the applying member. By

35 placing this member or gage in close proximity to the brush, or other member which applies the cement, it may be caused to limit the application of cement in this direction. Preferably, I employ as a gage a disk rotatably mounted and having a thin edge for

40 contact with the surface of the work being cemented. The gage is shown herein as supported on a bracket projecting from the frame of the apparatus, and on this bracket 45 at the opposite side of the applying member from the gage is preferably mounted a work-rest, which in cementing shoes for foxings contacts with the shoe bottom.

Another object of the invention is to operate 45 the movable applying member effectively. I attain this by connecting to the carrier for the applying member at a plurality of points means for actuating it. The

brush or other suitable applying member is thereby driven in a plurality of directions, 55 which may be so related as to cause it to sweep over the work, rise therefrom and return clear of the work for a fresh stroke. I have illustrated the applying member as supported upon one of the actuating or 60 power members, as an eccentric, and connected to another actuating member, as a crank. The eccentric is preferably carried upon the cement tank and provided with a passage through, which cement is fed to a 65 passage in the carrier of the applying member.

In connection with the following description of a particular embodiment of the invention illustrated by the accompanying 70 drawing, other objects will appear.

In this drawing, Figure 1 is a partial side elevation of my improved apparatus, with portions in section;

75 Fig. 2 is an enlarged sectional detail on the line 2—2 of Fig. 1; and

Fig. 3 is a perspective view of a bottom-rest and gage line with their supporting bracket.

Upon a suitable frame 10 is mounted a 80 cement tank 12, and journaled near the bottom of this tank is a horizontal shaft 14 projecting through an opening 16 in the tank wall. The shaft 14 is rotated through gearing 18 from a main shaft 20, journaled 85 in the frame below the tank and driven from a convenient source of power by a belt (not shown) operating over a pulley 22. Outside the tank the shaft 14 is surrounded by an eccentric sleeve 24 spaced from it to 90 furnish an intermediate passage 26. The connection between the shaft and sleeve is preferable through a block 28 pinned to the shaft and sleeve and being of less width than the passage, so that openings are left 95 at each side to permit the flow of cement. Partly within the tank and partly in the passage 26, the shaft 14 carries a worm 30 by which the cement is advanced outwardly through the passage.

100 Supported upon the eccentric is a carrier member 32, at the end of which farthest from the tank is a downward angular extension 34 containing a vertical socket to receive a brush holder 36, which is fixed in 105 the socket by a set screw 38. The holder

has an inclined end 40 provided at one side with a socket, in which may be placed a brush or other applying member 42 held by a thumb screw 44 threaded through the 5 outer wall of the socket. The passage 26 through the eccentric sleeve is continued at 46 through the extension 34 and the brush holder, and has at its lower end a nozzle 48 opening at its side in close proximity to the 10 brush 42. To control the flow of cement through the passage, the passage 46 in the brush holder has a valve 50 held normally closed by a spring 52 connecting an arm 54 fast on the valve stem with a bracket 56 15 rising from the brush carrier. Since both the valve arm and the bracket 56 move together with the brush in its applying stroke, this causes no variation in the tension of the spring. To allow the operator 20 to open the valve to permit cement to flow through the nozzle to the brush, there is pivoted on the floor below the apparatus a treadle 58 joined to the arm 54 by a connecting rod 60. The depression of the 25 treadle rotates the valve against the tension of the spring 52 to open it. Since the throw of the eccentric 24 is short, the relative movement between the valve, which is moved with the carrier by the eccentric, and the 30 treadle, pivoted to a relatively fixed point, is slight and has no ill effect on its operation.

In addition to the vertical movement imparted to the brush carrier by the eccentric 35 24, there is a horizontal component to cause points at the applying surface of the brush to describe ellipses. This horizontal movement is produced by an actuating member consisting of a crank pin 62 projecting from 40 the end of the shaft 20 and extending between the divided ends 64, 64 of an arm 66 depending from the carrier 32. The resulting movement of the brush is shown by the dot and dash elliptical line in Fig. 2 of the drawings. In its rearward movement 45 from the operator, it passes in contact with the work along the line indicated at *a*. It then rises as shown at *b*, returning out of contact with the work at *c* and descending at *d* for the succeeding stroke.

Fixed to the side of the frame 10 below the end of the shaft 20 carrying the crank pin is a bracket 68 having an upwardly extending angular end 70 adjacent to the brush holder. To this end 70 of the bracket is fixed a U-shaped horizontal extension or yoke 72, between the arms of which extension the brush moves. On the outer arm is carried a gage member. This is preferably 55 in the form of a disk 74 movably mounted at 76 upon the extension arm. The arm is shown as inclined outwardly and upwardly from the brush, so that the reduced edge 78 of the disk is brought into close proximity 60 with the outer side of the brush, yet leaving

the latter with its holder and associated elements ample space for their movement. The diameter of the gage disk and its relation to the path of movement of the brush is such that said brush, during substantially 70 its entire movement, is opposite the disk, the interposed gage thus limiting the flow of cement over the line traced by its edge upon the upper. In a way formed in a lower horizontal surface 80 of the bracket 68 is 75 movably mounted a work-rest 82, adjustably secured in place by a thumb screw 84 extending through a slot in the gage arm and being threaded into the bracket. At the outer extremity of the work-rest is a vertical 80 contact face 86, which is herein illustrated as parallel to the path of oscillation of the brush, and against which the bottom of the shoe being cemented is pressed by the operator to guide it in correct relation to the 85 brush. To cause the applying edge 88 of the brush to rest uniformly against the curve of the upper to which the cement is to be applied, this edge is inclined, as indicated at 88, so that it approximately conforms to 90 this curvature.

In using this apparatus, the tank 12 is supplied with cement, and, power being applied to the pulley 22, the cement is forced from the tank by the worm 16 through the 95 passage 26 and its continuation 46, and when the valve 50 is opened, this cement is delivered through the nozzle 48 against the side of the brush. The operator places the 100 lasted upper which is to be cemented with its bottom against the face 86 of the work-rest, with the edge 78 of the gage disk contacting with it to define the upper line of the foxing, and moves it beneath the oscillating brush 88, the applying edge of which 105 extends transversely of the upper. This brush, as has already been pointed out, during its travel in one direction sweeps over the work, applying thereto cement from the 110 nozzle 48, and then returns out of contact with the upper for another stroke. The cement is thus brushed out effectively, its passage beyond the line of the foxing being prevented by the interposition of the gage disk 74. The rotation of this disk allows the 115 movement of the work under the brush with little resistance. To allow the relation of the gage disk to the brush to be altered, the yoke 72 may be attached to the bracket by a screw 77 passing through a slot 79 in the 120 inner arm of the yoke, while the yoke may be in sections joined by a screw 81 threaded into one section and extending through a slot 83 in the other. By the adjustment first mentioned the position of the disk with 125 reference to the path of the brush may be altered, while by the second, the distance between the disk and brush may be changed and therefore the location of the edge of the band of cement applied.

Having thus described my invention, what I claim as new and desire to secure by Letters Patent of the United States is:—

1. In a cementing apparatus, a movable cement-applying member, and a member situated at one side of the applying member and arranged to define the line between the coated and uncoated areas, it extending substantially the full length of the path of movement of the applying member. 70
2. In a cementing apparatus, a movable cement-applying member, and a cement gage situated in proximity to the applying member along substantially the entire length of its path of movement. 75
3. In an apparatus for cementing the uppers of shoes for foxings, a movable member for applying cement to the upper, and a gage along which the applying member moves, said gage having an edge for contact with the upper in close proximity to the applying member and limiting the application of cement in this direction to a line defining the edge of the foxing. 80
4. In a cementing apparatus, a movable cement-applying member, and a rotatable gage-disk situated at one side of the applying member for contact with the surface of the work over which the applying member operates. 85
5. In a cementing apparatus, a movable cement-applying member, and a rotatable gage-disk situated at one side of the applying member and having a thin edge for contact with the surface of the work being cemented adjacent to the brush. 90
6. In a cementing apparatus, an oscillatory cement-applying brush, and a gage-disk movably mounted at one side of the path of oscillation of the brush. 95
7. In a cementing apparatus, an oscillatory cement-applying brush, a gage-disk mounted at one side of the path of oscillation of the brush, and means arranged to permit the position of the disk along the path of the brush to be varied. 100
8. In a cementing apparatus, a movable cement-applying member, a rotatable gage-disk situated at one side of the applying member for contact with the work, and means arranged to permit the distance between the applying member and disk to be varied along the surface being cemented. 105
9. In a cementing apparatus, an oscillatory cement-applying brush, and a gage-disk rotatably mounted at one side of the path of oscillation of the brush, the brush in substantially its entire movement being opposite the disk. 110
10. In a cementing apparatus, an oscillatory cement-applying brush, and a gage-disk movably mounted at one side of the path of oscillation of the brush and being inclined with respect thereto. 115
11. In a cementing apparatus, an oscillatory cement-applying brush, and a gage-disk movably mounted at one side of the path of oscillation of the brush and being inclined to the general contour of the portion to which the cement is to be applied and cement-arresting means situated adjacent to the brush. 120
12. In an apparatus for cementing the uppers of shoes for foxings, a cement-applying brush having an edge extending transversely of the shoe upper and being inclined to the general contour of the portion to which the cement is to be applied and cement-arresting means situated adjacent to the brush. 125
13. In an apparatus for cementing the uppers of shoes for foxings, an oscillatory cement-applying brush having an edge extending transversely of the shoe upper and being inclined to the general contour of the portion to which the cement is to be applied, a bottom rest provided with a contact face substantially parallel to the path of oscillation of the brush, and cement-arresting means situated at the opposite side of the brush from the bottom rest. 130
14. In a cementing apparatus, a frame, a cement-applying member mounted thereon, an arm projecting from the frame toward the applying member, and a work-rest and a gage carried by the arm. 135
15. In a cementing apparatus, a frame, a cement-applying member mounted thereon, an arm projecting from the frame toward the applying member, and a work-rest and a gage carried by the arm at opposite sides of said member. 140
16. In a cementing apparatus, a frame, a cement-applying member mounted thereon, an arm projecting from the frame toward the applying member, a work rest fixed to the arm, and a gage-disk rotatable upon the arm. 145
17. In a cementing apparatus, a frame, a cement-applying member mounted thereon, an arm projecting from the frame toward the applying member and having a horizontally extending portion and an upwardly extending portion, and members for contact with the work mounted on both the horizontally and upwardly extending portions. 150
18. In a cementing apparatus, a frame, a cement-applying member mounted thereon, an arm projecting from the frame toward the applying member and having a horizontally extending portion and an upwardly extending portion, a work-rest fixed to the horizontal portion, and a cement gage mounted on the upwardly extending portion. 155
19. In a cementing apparatus, a frame, a cement-applying member mounted thereon, an arm projecting from the frame toward the applying member and having a horizontally extending portion and an upwardly extending portion, a bottom-rest adjustable 160

upon the horizontal portion, and a gage-disk rotatable upon the upwardly extending portion.

20. In a cementing apparatus, a cement-applying member, a carrier therefor, and actuating means for the applying member connected to the carrier at a plurality of points.

21. In a cementing apparatus, a cement-applying member, a carrier therefor, and a plurality of driving members for the carrier.

22. In a cementing apparatus, an oscillatory cement-applying member, means for moving the applying member in one direction, and independent means for moving the applying member in another direction.

23. In a cementing apparatus, two movable power members, and a cement-applying brush supported on one of the power members, there being a connection between the brush and the other power member.

24. In a cementing apparatus, an applying brush, a brush carrier, an eccentric on which the carrier is supported, a crank to which the carrier is connected, and means for rotating the eccentric and crank.

25. In a cementing apparatus, a tank, an eccentric rotatable upon the tank and being provided with a passage leading therefrom,

and an applying member including a carrier having a passage communicating with the passage in the eccentric.

26. In a cementing apparatus, a tank, an eccentric rotatable upon the tank and being 35 provided with a passage leading therefrom, an applying member including a carrier having a passage communicating with the passage in the eccentric, and a cement-feeding member extending from the tank into 40 the last-named passage.

27. In a cementing apparatus, a tank, an eccentric rotatable upon the tank and being provided with a passage leading therefrom, an applying member including a carrier 45 having a passage communicating with the passage in the eccentric, an arm extending from the carrier, and a rotatable shaft having a crank engaging the arm.

28. In a cementing apparatus, a tank, a 50 cement-applying member, an oscillatory carrier for the applying member having a passage connected with the tank, a valve mounted upon the carrier in the passage, and a spring connecting the valve and carrier member.

In testimony whereof I have signed my name to this specification.

JOHN W. COSGROVE.
